(57) **CLAIM**

The ornamental design for a movable cabinet, as shown and described.

DESCRIPTION

FIG. 1 is a front elevational view of a movable cabinet, showing my new design;

FIG. 2 is a side elevational view thereof;
FIG. 3 is a back elevational view thereof;
FIG. 4 is a bottom plan view thereof;
FIG. 5 is a top plan view thereof;
FIG. 6 is a front perspective view thereof;
FIG. 7 is a perspective view thereof;
FIG. 8 is a side perspective view thereof;
FIG. 9 is a first partial perspective view thereof;
FIG. 10 is a second partial perspective view thereof;
FIG. 11 is a front elevational view of a movable cabinet, showing a second embodiment of my new design;
FIG. 12 is a side elevational view thereof;
FIG. 13 is a back elevational view thereof;
FIG. 14 is a bottom plan view thereof;
FIG. 15 is a top plan view thereof;
FIG. 16 is a front perspective view thereof;
FIG. 17 is a side perspective view thereof;
FIG. 18 is a back perspective view thereof;
FIG. 19 is a first partial perspective view thereof;
The second embodiment of my design is also represented by FIG. 9;
FIG. 20 is a perspective view of a movable cabinet, showing a third embodiment of my design, the third embodiment is also represented by FIGS. 9 and 11 through 18;
FIG. 21 is a front elevational view of a movable cabinet, showing a fourth embodiment of my design;
FIG. 22 is a perspective view thereof;
FIG. 23 is a bottom perspective view thereof;
The fourth embodiment of my design is also represented by FIGS. 9, 14, and 15;
FIG. 24 is a front elevational view of a movable cabinet, showing a fifth embodiment of my design;
FIG. 25 is a front perspective view thereof;
FIG. 26 is a first perspective view thereof;
FIG. 27 is a second perspective view thereof; and,
FIG. 28 is a bottom perspective view thereof.
The fifth embodiment of my design is also represented by FIGS. 9, 12-15, 17, and 18.
The broken lines shown in the figures are for illustrative purposes only and form no part of the claimed design.

1 Claim, 28 Drawing Sheets
